UNITED STATES PATENT OFFICE.

AMBROSE FLEMING, OF ALEXANDRIA, VIRGINIA.

MAGAZINE PENCIL.

Application filed August 18, 1922, Serial No. 582,693. Renewed January 27, 1925.

To all whom it may concern:

Be it known that I, AMBROSE FLEMING, a citizen of the United States, residing at Alexandria, in the county of Alexandria and 5 State of Virginia, have invented certain new and useful Magazine Pencils, of which the following is a specification.

My present invention is a magazine pencil of the screw feed type and it primarily has 10 for its objects to provide a pencil the parts of which are so designed and correlated that they may be assembled without the use of solder, etc., and further to provide a pencil which will be fool proof, i. e., one which 15 functions properly at all times, both in its writing character and in the supplying of leads, one after another, within the capacity of the magazine.

It is another object of the invention to 20 provide a pencil which is of a sturdy construction and cannot get out of order during ordinary use.

In its general nature my pencil comprises 25 a barrel or casing within which a lead receiver and guide is fastened and a magazine for the leads is arranged to fit over a portion of the lead receiver and guide and deliver the leads, one after another, to the receiver upon turning the magazine, a nose 30 being screwed to the barrel and being so correlated to the magazine that as the nose is unscrewed and screwed up again the magazine will be caused to deliver a lead to the receiver; there is also provided a screw operated push rod which feeds the lead along 35 the receiver through the nose, the screw being operated by a rotatable head in the end of the pencil opposite to the nose, there being provision whereby to eliminate longitudinal thrusts on the screw when the push rod is at either limit of its stroke.

In its more specific nature the invention furthermore embodies those novel details of construction, combination and arrangement 45 of parts, all of which will be fully described and then be specifically pointed out in the appended claims, reference being had to the accompanying drawings, in which:—

Figure 1 is a longitudinal section on an 50 enlarged scale of my invention, the parts being in the position where a lead is ready for writing purposes.

Figure 2 is a view similar to Figure 1, parts being broken away and shown in ele-

vation, indicating the position of the parts 55 at the time a new lead is delivered into the lead receiver and guide from the magazine.

Figure 3 is a cross section on the line 3—3 of Figure 1.

Figure 4 is a cross section on the line 4—4 60 of Figure 1.

Figure 5 is a cross section on the line 5—5 of Figure 1.

Figure 6 is a detail side elevation, parts 65 being broken away of the feed screw.

Figure 7 is a cross section on the line 7—7 of Figure 2.

Figure 8 is a cross section on the line 8—8 of Figure 2.

Figure 9 is a detail perspective view of 70 a portion of the lead receiver and guide showing the manner of inserting the push rod.

Figure 10 is a detail side elevation of the 75 nose bushing.

Figure 11 is a side elevation of the magazine bearing bushing.

Figure 12 is a detail side elevation of the part bushing.

Figure 13 is a detail side elevation, parts 80 being broken away of the lead receiver and guide.

Figure 14 is a detail perspective view of the lead magazine.

In the drawings in which like numerals 85 of reference indicate like parts in all of the figures, 1 is the barrel or casing which contains a partition bushing 2 that is provided with an annular groove 3, the bottom of which is serrated as at 4, see Figure 12, 90 whereby when the barrel 1 is rolled or pressed into the groove 3, as at 26, the bushing 2 will be rigidly and immovably held within the barrel, not only against longitudinal motion but against rotation as well. 95

The bushing 2 is provided with a middle bore in which the lead receiver and guide 8 is tightly fitted by shrinking the bushing 2 on the lead receiver or guide or fastening the same in any other permanent way. The 100 bushing is also provided with an end bore 6 forming a bearing for the end of the feed screw 18, and it also has an end bore 7 forming a bearing for one end of the magazine 32.

8 designates the lead receiver and guide which extends the full length of the barrel 1 and well into the nose 35 of the pencil

holder. The lead receiver and guide 8 where it passes through the central bore 5 of the bushing 2 is unslotted, as at 9, so as to form a continuous tube in the length 5 of the bore 5. The lead receiver and guide is provided with a lead receiver socket 11, the socket 11 extending the full length of the magazine 32, which will be again referred to hereinafter.

10 The lead receiver and guide is provided with an unslotted end 10 which projects through the washer 43 into the nose of the pencil.

12 designates a key slot in the lead receiver and guide, in which the key 17 of the push rod 16 is longitudinally movable. At the end of the key slot 12 the lead receiver and guide has a portion removed, as at 18, so that by heating the tubular member at 14 and bending it as shown in Figure 9 the push rod 16 may be inserted, after which the parts 8-8 (Figure 9) will again bend into alignment and when cooled down will be as strong as before.

25 The lead receiver and guide has a slit end 15 for a purpose presently explained.

18 is the feed screw which in the present embodiment of my invention is tubular in character and has one end projected into the socket 6 of the bushing 2. It also has stops 19 at each end of the screw-way so as to engage the sides of the key 17 and prevent longitudinal thrusts of the screw when the key 17 is at either end of the structure. 20 is a socketed head which is shrunk or otherwise rigidly secured to the screw 18 and by which the screw is turned. The socketed head is shouldered at 21 and has a threaded end 22 over which the cap 24 is screwed and the socket and cap enclose a chamber 23 in which an eraser 25 may be held.

The slit end 15 of the lead receiver and guide, when the parts are assembled, is upset or riveted over, see Figure 1, thus holding the socket 20 in place and holding the screw 18 in position against longitudinal movement while allowing the screw to be freely turned within the barrel 1.

50 27 is a magazine bearing bushing which
is provided with an annular groove 28 ser-
rated at its bottom, as at 29, (see Figure
11) and this magazine bushing is rigidly
fastened in the end of the barrel 1, oppo-
55 site that having the head, by pressing or
turning a groove 42 in the barrel as shown
in Figure 1, thus holding the bushing im-
movable in the barrel. The bushing 27

movable in the barrel. The bushing 27 is also provided with a threaded counterbore 30 and it has a bearing bore 31 for the magazine 32. The magazine 32 is a cylinder having a V-shaped depression or groove 33 to form a cutoff and guide finger for the leads contained in the magazine (see Figure 13) and it also has an annular bead

34 which rests against the bushing 27 when the magazine is fitted in place with its end in the bearing socket 7 of the partition bushing 2, see Figures 1 and 2.

The magazine 32 projects into the pencil holder nose 35, one end of which, 36, is provided with a nose bushing 38 while the other end has a pencil outlet 37. The nose bushing 38 has a threaded end 39 to enter the threaded counterbore 30 of the magazine bearing bushing 27. The bushing 38 has a knurled groove 40 into which the nose shell is rolled or pressed, as at 45, to hold the bushing 38 immovable in the nose 35. 70 75

43 is a disk held in the nose by retaining friction and having a beveled entrance 44 for the easy passage of the end of the lead receiver and guide when assembling the parts.

46 is an indicator on the barrel 1 which enables the user to hold the barrel in position with the socket 11 of the lead receiver and guide uppermost. The indicator 46 may be of any desired kind, but preferably in the form of a retaining clip of the usual construction.

In use when it is desired to fill the magazine with leads the nose 35 is unscrewed and removed. The leads are inserted in the magazine around the lead receiver and guide, assuming the position shown in Figures 4 and 5. It should be understood, of course, that when the magazine of the pencil is empty the screw 18 is turned to bring the key 17 back to the right hand end of the pencil (see Figure 2). In order to feed the leads forwardly the screw 18 is turned in a clockwise direction to move the key 17 toward the nose of the pencil to project as much lead as desired, see Figure 1. 103

After using up the first lead a second one may be supplied by turning the key 17 to the position shown in Figure 2, and while holding the barrel with the indicator 46 uppermost (Figure 2) the nose 35 is unscrewed one complete revolution or more (one being usually sufficient) whereupon a new lead will be dropped into the lead receiver and guide (see Figure 8) after which the nose 35 is screwed home again to the position shown in Figure 11. Then the lead may be advanced by the action of the screw 18 as before. This operation of supplying the lead receiver and guide with new leads may be repeated again and again until the supply of leads in the magazine have become exhausted.

I wish to call special attention to the fact that in my construction of pencil the parts are all mechanically connected, i. e. held together without the use of solder, brazing, or the like so therefore there is no danger of the parts separating or pulling apart during the normal usage of the pencil. 125

From the foregoing description, taken in 130

connection with the accompanying drawings, it is thought that my invention will be clear to those skilled in the art.

What I claim is:

5. 1. In a magazine pencil, a barrel, a nose rotatable on the barrel, a lead receiver and guide mounted in and rotatable with said barrel and projecting into said nose, a push rod in said lead receiver and guide, a feed screw receiving a portion of said lead receiver and guide, said push rod having a key engaging said screw, a lead magazine rotatably mounted in said barrel and projected into said nose, means connecting said nose and magazine to turn together, said lead receiver projecting through said magazine, and means to turn said screw, said screw being rotatable with respect to the barrel.
10. 2. In a magazine pencil, a barrel, a nose rotatable on the barrel, a lead receiver and guide mounted in and rotatable with said barrel and projecting into said nose, a push rod in said lead receiver and guide, a feed screw receiving a portion of said lead receiver and guide, said push rod having a key engaging said screw, a lead magazine rotatably mounted in said barrel and projected into said nose, means connecting said nose and magazine to turn together, said lead receiver projecting through said magazine, and means to turn said screw, said lead receiver and guide having a lead receiving slot and a push rod key slot, said screw being rotatable with respect to the barrel.
15. 3. In a magazine pencil, a barrel, a nose rotatable on the barrel, a lead receiver and guide mounted in and rotatable with said barrel and projecting into said nose, a push rod in said lead receiver and guide, a feed screw receiving a portion of said lead receiver and guide, said push rod having a key engaging said screw, a lead magazine rotatably mounted in said barrel and projected into said nose, means connecting said nose and magazine to turn together, said lead receiver projecting through said magazine, and means to turn said screw, said lead receiver and guide having a lead receiving slot, a push rod key slot, and means on said barrel to indicate the position of said lead receiving slot, said screw being rotatable with respect to the barrel.
20. 4. In a magazine pencil, a barrel, a nose rotatably mounted on said barrel, a partition bushing located fixedly in the barrel and recessed to provide a magazine end-bearing, a magazine bearing bushing fixedly located in said barrel and having a magazine bearing, a lead magazine rotatably mounted in said barrel and having a magazine bearing, a lead magazine rotatably mounted in said bearings, a nose bushing fixedly held in said nose and having a bearing for said magazine, said magazine and said nose bushing being keyed together, a disk in said nose constituting a closure for one end of said magazine and having a bearing aperture, a
25. 5. In a magazine pencil, a barrel, a nose rotatably mounted on said barrel, a partition bushing located fixedly in the barrel and recessed to provide a magazine end-bearing, a magazine bearing bushing fixedly located in said barrel and having a magazine bearing, a lead magazine rotatably mounted in said bearings, means holding said magazine against longitudinal movement in said bearings, a nose bushing fixedly held in said nose and having a bearing for said magazine, said magazine and said nose bushing being keyed together, a disk in said nose constituting a closure for one end of said magazine and having a bearing aperture, a
30. 6. In a magazine pencil, a barrel, a nose rotatably mounted on said barrel, a partition bushing located fixedly in the barrel and recessed to provide a magazine end-bearing, a magazine bearing bushing fixedly located in said barrel and having a magazine bearing, a lead magazine rotatably mounted in said bearings, a nose bushing fixedly held in said nose and having a bearing for said magazine, said magazine and said nose bushing being keyed together, a disk in said nose constituting a closure for one end of said magazine and having a bearing aperture, a
35. 7. In a magazine pencil, a barrel, a nose rotatably mounted on said barrel, a partition bushing located fixedly in the barrel and recessed to provide a magazine end-bearing, a magazine bearing bushing fixedly located in said barrel and having a magazine bearing, a lead magazine rotatably mounted in said bearings, a nose bushing fixedly held in said nose and having a bearing for said magazine, said magazine and said nose bushing being keyed together, a disk in said nose constituting a closure for one end of said magazine and having a bearing aperture, a

- lead receiver and guide fixedly mounted in said partition bushing and projecting through said magazine and said lisk into said nose, said partition bushing having a feed screw bearing recess, a feed screw mounted on said lead receiver and guide and having bearing in said last named bearing recess, a head fixed to said feed screw and closing one end of said barrel, means for holding said feed screw head against longitudinal movement of said barrel, a push rod mounted in said lead receiver and guide and having a key to engage said feed screw, said lead receiver and guide having a key slot.

8. In a magazine pencil, a barrel, a nose rotatably mounted on said barrel, a partition bushing located fixedly in the barrel and recessed to provide a magazine end-bearing, a magazine bearing bushing fixedly located in said barrel and having a magazine bearing, a lead magazine rotatably mounted in said bearings, a nose bushing fixedly held in said nose and having a bearing for said magazine, said magazine and said nose bushing being keyed together, a disk in said nose constituting a closure for one end of said magazine and having a bearing aperture, a lead receiver and guide fixedly mounted in said partition bushing and projecting through said magazine and said disk into said nose, said partition bushing having a feed screw bearing recess, a feed screw mounted on said lead receiver and guide and having bearing in said last named bearing recess, a head fixed to said feed screw and closing one end of said partition bushing, a push rod mounted in said lead receiver and guide and having a key to engage said feed screw, said lead receiver and guide having a key, and means to avoid end thrust of said feed screw by said key when said key reaches the ends of its path of travel.

9. In a magazine pencil, a barrel, a partition bushing fixed in said barrel, a lead receiver and guide fixed in said bushing, a magazine for supplying leads to said receiver and guide, a nose through which the leads are projected, a head rotatable at the end of said barrel, a tubular feed screw fixed at one end to said head and at the other end having bearing in a recess in said partition bushing, said lead receiver and guide projecting through said screw and being riveted over to secure said screw against longitudinal movement, a push rod in said lead receiver and guide and having a screw engaging key.

10. In a magazine pencil, a barrel, a partition bushing fixed in said barrel, a lead receiver and guide fixed in said bushing, a nose through which the leads are projected, a head rotatable at the end of said barrel, a tubular feed screw fixed at one end to said head and at the other end having bearing in a recess in said partition bushing, said lead receiver and guide projecting through said screw and being riveted over to secure said screw against longitudinal movement, a push rod in said lead receiver and guide and having a screw engaging key.

11. In a magazine pencil, a barrel, a nose screwed into one end of said barrel, a head rotatably mounted in and projecting from the other end of said barrel, a lead receiver and guide fixedly mounted within said barrel and projecting into said nose and into said head, the nose end of said receiver and guide having a lead receiving slot while the other end thereof has a key slot, a push rod mounted in said lead receiver and guide and having a key operating in said key slot, a feed screw rigidly mounted on said head and engaging said key to project and retract said push rod, a lead magazine rotatably mounted in said barrel, a connection between said nose and said magazine whereby as said nose is screwed and unscrewed said magazine will be turned with said nose to deliver leads to said lead receiver and guide.

12. In a magazine pencil, a barrel, a nose screwed into one end of said barrel, a head rotatably mounted in and projecting from the other end of said barrel, a lead receiver and guide fixedly mounted within said barrel and projecting into said nose and into said head, the nose end of said receiver and guide having a lead receiving slot while the other end thereof has a key slot, a push rod mounted in said lead receiver and guide and having a key operating in said key slot, a feed screw rigidly mounted on said head and engaging said key to project and retract said push rod, a lead magazine rotatably mounted in said barrel, a connection between said nose and said magazine whereby as said nose is screwed and unscrewed said magazine will be turned with said nose to deliver leads to said lead receiver and guide, said magazine having an open end accessible for loading purposes when said nose is removed from said barrel, said nose having provisions for closing said open end of said magazine when said nose is screwed in place.

AMBROSE FLEMING.
